Inventor:
Robert P. Standeford

UNITED STATES PATENT OFFICE.

ROBERT PRICE STANDEFORD, OF SIMLA, COLORADO.

BUTT AND CASING GAGE.

1,243,456.

Specification of Letters Patent.

Patented Oct. 16, 1917.

Application filed October 2, 1916. Serial No. 123,279.

To all whom it may concern:

Be it known that I, ROBERT PRICE STANDEFORD, a citizen of the United States, residing at Simla, in the county of Elbert and 5 State of Colorado, have invented a new and useful Butt and Casing Gage, of which the following is a specification.

My invention relates to improvements in gages, and the object of this invention is to 10 provide a useful tool, by the use of which the correct measurements and markings preparatory to cutting mortises for door butts, and the marking preparatory to the cutting of casings to the proper lengths may 15 be accomplished with greater facility than by the use of tools as heretofore made.

I attain these objects by the mechanism illustrated in the accompanying drawing, in which Figure 1 is a perspective view of the 20 entire tool, Fig. 2 is an end elevation particularly showing a sectional view of the body, and the guide formed at one edge of the body.

The gage may be made of metal or wood, 25 preferably of sheet steel. It consists essentially of a body plate 1 having a guide plate 2 extending at a right angle to the face of the body or plate 1. The body plate 1 of the tool has a stepped isosceles triangular 30 opening 3 in the face of plate 1, the unequal side of which extends the greater length of plate 1 parallel and adjacent to guide 2. The equal sides of opening 3 are provided with notches the faces of which are parallel 35 and at right angles respectively to the unequal side of opening 3. All the parts are marked on their faces near their working edges with graduations indicating inches and fractions thereof. The graduations ad-

40 jacent to the notched portion of opening 3 indicate the distance the notches are from the union of the two plates 1 while the graduations on each end of plate 1 indicate measurements to correspond with the 45 stepped sides of opening 3. The graduations on the side edge of plate 1 indicate inches and fractions thereof from one end 7 of plate 1. The openings 4 in the angle of plate 1 and guide 2 extend at right angles to

50 the face of plate 1 of varied depths from plate 1 as $\frac{1}{16}$ inch $\frac{3}{32}$ inch $\frac{1}{8}$ inch and $\frac{5}{32}$ inch. Any number of openings can be used; there 55 are 4 shown in the drawing. The ends 5 of guide 2 extend at right angles to that portion of plate 1 indicated at 6. The ends 7

of plate 1 extend at right angles to the side edges of plate 1.

In using the tool for marking a door to indicate the lines on which to cut to form a mortise for a butt, place guide 2 parallel 60 against the face of the door with plate 1 parallel against the edge of the door. A line drawn with a marker against the upper end 7 will give the upper end of the mortise. The location of the bottom end of the 65 mortise is found by the use of the scale of inches on the edge of plate 1 and marked in accordance thereto; the width of the mortise is indicated by placing a marker into the notch in opening 3 which indicates the 70 distance the inner edge of the butt is to be located from the face of the door. The tool is then drawn with guide 2 and plate 1 maintained in contact with the face and edge of the door the length of the mortise 75 to be cut. The depth of the mortise is indicated by placing a marker in the proper opening 4 and drawing the tool along the edge of the door the length of the mortise. The notches in opening 3 are equally spaced 80 from each side edge of plate 1. To use the tool in laying out a mortise on a rabbeted door jamb, place the inner edge of plate 1 against the stop face of the rabbet, place a marker in the proper notch in opening 3. 85 This when drawn the length of the butt will give the inner line of the mortise to be cut, place the tool, plate 1 on edge of the door and guide 2 on inner face of the door and place a marker in the notch in opening 3 90 near guide 2 that corresponds to the one used in marking the jamb. This will give the inner line of the mortise to be cut on the door.

This mechanism prevents the marker following the grain of the wood outside the desired line to be cut; its open construction allows a very accurate and quick adjustment of the tool to mark the inner line of the 95 mortise.

In using the tool to mark a side casing preparatory to cutting to proper length, first cut the bottom end of casing to fit its abutment, then set the casing in its proper position placing the tool on casing with 105 guide 2 held parallel against the side jamb to be cased and plate 1 flat on the face of the casing to be marked, then raise the tool until the end 5 of guide 2 comes in contact with the head jamb of the opening to be 110

cased; then by drawing a pencil or marker against the top end 7 of plate 1 the mark will show the proper length to cut the casing. The other side casing is handled in like manner with the other end of the tool up, thus securing a uniform parallel margin on the head jambs of all openings to be cased.

What I claim and desire to secure by Letters Patent, is—

1. A butt and casing gage consisting of a single piece of sheet material formed of two rectangular plates, one a body plate the other a guide plate, at right angle to each other, the body plate having a stepped isosceles triangular opening therein, the unequal side of said opening being parallel to the edge formed by the union of the two plates.
2. A butt and casing gage consisting of a single piece of sheet material formed of two rectangular plates, one a body plate the other a guide plate, at right angle to each other, the body having a stepped isosceles triangular opening therein, the equal sides of said opening having equal stepped

notches, the faces of which are parallel respectively to the side edge and each end edge of the body plate.

3. A butt and casing gage consisting of a single piece of sheet material formed of two rectangular plates, one a body plate the other a guide plate, at right angle to each other, each plate having in the edge forming the union of the two plates, right angled openings extending varying depths into the guide plate.

4. A butt and casing gage consisting of a single piece of sheet material formed of two rectangular plates, one a body plate the other a guide plate, at right angle to each other, the ends of the guide plate forming shoulders to strike an abutment substantially as set forth.

5. A butt and casing gage consisting of a single piece of sheet material formed of two rectangular plates, one a body plate the other a guide plate at right angle to each other, the body plate projecting beyond the guide plate at each end.

ROBERT PRICE STANDEFORD.
